UNITED STATES PATENT OFFICE.

MAX VON FÖRSTER, OF BERLIN, GERMANY.

SHELL.

SPECIFICATION forming part of Letters Patent No. 333,091, dated December 22, 1885.

Application filed July 7, 1885. Serial No. 170,846. (No model.)

To all whom it may concern:

Be it known that I, MAX VON FÖRSTER, a subject of the King of Prussia, residing at Berlin, Germany, have invented certain Improvements in Projectiles, of which the following is a specification.

My invention consists of certain improvements in that class of hollow projectiles which are filled with an explosive; and the main object of my invention is to so construct a projectile of this class that the contents of the projectile will be kept firm and solid, and this object I attain by embedding the contents of the projectile in paraffine or equivalent material, which is poured in in a liquid state and solidifies around the grains of the explosive, as fully described herein after.

In the accompanying drawings, Figure 1 is a sectional view of the upper end of a projectile embodying my improvements. Fig. 2 is a plan view of the priming-cartridge detached. Fig. 3 is a sectional view of a modification, and Fig. 4 is a plan view of the same.

Referring to Fig. 1, *d* represents the walls of the projectile, which has at its point an opening or mouth for the introduction of the explosive material of the cartridge, and for the reception of the fuse *c*. The explosive substance *e*, in sufficiently small granular form, is introduced through the opening or mouth of the projectile until the latter is nearly filled. A cylinder, *b*, made of a compressed mass of the same or of another explosive substance which will produce a detonation of the explosive material *e*, and serves for a priming-cartridge, is now introduced into the hollow projectile. A space is left around the upper edge of the cartridge, and liquid paraffine is then poured into the hollow projectile. The paraffine fills up all the cavities between the several grains of the explosive substance, and between these grains and the walls *d* of the projectile it hardens quickly and converts the whole charge into a rigid solid body.

Instead of introducing the priming-cartridge before pouring in the paraffine, a cylinder made of any other solid material—of metal, for instance—may previously be introduced,

the paraffine filled in, and the cylinder may then be taken out after the paraffine has hardened. A hollow space is thus formed for the reception of the priming-cartridge.

Within the priming-cartridge *b* is the usual copper cap, *a*, which consists of a tube closed at one end and open at the other, and filled in part with fulminating mercury.

The mouth of the projectile above the priming-cartridge is closed by the fuse *c*, the open end of the cap *a* being toward the fuse. The priming-cartridge is exploded by the flame from the fuse in the usual manner.

In Figs. 3 and 4 I have illustrated a modified form of priming cartridge or cap, the cap *a* being provided with a laterally-extending rim, *a'*, and around the cap is placed a rubber ring, *b'*, by which the cap is fixed in the metal cylindrical extension *c'* of the fuse. The rim *a'* at the open end of the cap is of sufficient strength to prevent its being bent by pressure or shocks. The lower end of the copper cap projects into the priming-cartridge in the usual manner.

Instead of using paraffine to solidify the explosive, wax may be employed, or a mixture of wax and paraffine, or solid distilled fatty acids—as, for instance, palmitic acid, inorganic acid, stearic acid, or any equivalent substance which does not prevent the transfer of the detonation from one particle of the explosive substance to another.

When porous explosive substances are employed, I protect the grains of the explosive material and also the priming-cartridge by a coating against the entrance of the paraffine, so far as is necessary to maintain its explosive character. In nitrated cellulose—such as gun-cotton, for instance—this coating may easily be obtained by dipping the pieces into a solvent of the nitro-cellulose. Where ordinary black powder is employed, a coating is not necessary.

If the priming-cartridge is made of nitro-cellulose, and the fluid which dissolves the nitro-cellulose is poured into the projectile, the copper cap will be placed therein while the dissolved parts of the wall are still wet, so that the cap will be fixed in the priming-cartridge as soon as the latter becomes dry.

I claim as my invention—

1. A hollow projectile having its explosive

contents embedded in paraffine or equivalent material to form the whole of said contents into a solid mass.

2. A hollow projectile having a granular explosive and a priming-cartridge both embedded in paraffine or equivalent material to form the whole contents of said projectile into a solid mass.

3. A hollow projectile containing a porous explosive having its granular contents embedded in paraffine or equivalent material, the grains

having a protective coating to prevent the entrance of the paraffine or equivalent into the same, substantially as described.

In testimony whereof I have signed my name to this specification, in the presence of two subscribing witnesses, June 17, 1885.

MAX VON FÖRSTER.
